2(BETA CARBOXY, ALPHA- OR BETA-THIOCARBOALKOXY-THIOLPROPIONAMIDO) BENZOTHIAZOLES

Edward B. Knott, Harrow, England, assignor to Eastman Kodak Company, Rochester, N. Y., a corporation of New Jersey

No Drawing. Application April 30, 1952,
Serial No. 285,301

10 Claims. (Cl. 260—305)

This invention relates to improvements in the production of photographic images, especially images on paper supports prepared from silver halide emulsions, and to new chemical compounds.

Silver halide emulsions are frequently subject to image degradation during processing, that is, during development, fixing, washing, toning, or other treatment and during the moist heat to which they are subjected on drying, as when prints are subjected to ferrotyping or hot-type glazing. This degradation of the image frequently manifests itself as "plumming" or "bronzing" of the image.

I have now found, however, that compounds which can be represented by the following two general formulas:

and

wherein R represents an alkyl group, such as methyl, ethyl, n-propyl, n-butyl, isobutyl, n-amyl, n-heptyl, n-octyl, etc., M represents a hydrogen atom or an alkali metal atom, e. g. sodium, potassium, etc., and Z represents the non-metallic atoms necessary to complete a heterocyclic nucleus of the benzothiazole series, are not only effective anti-plumming agents but upon prolonged standing, develop no objectionable color and show no increase in desensitizing properties.

It is, therefore, an object of my invention to provide a means for preventing image degradation in an exposed silver halide emulsion. Still another object is to provide new chemical compounds. Another object is to provide methods for making these new compounds. Another object is to provide photographic silver halide emulsions containing these new compounds. Other objects will become apparent from a consideration of the following examples and description.

Accordingly, I realize the above objects by providing the compounds represented by Formulas I and II above, which can be used to prevent undesirable image degradation in exposed silver halide emulsions. When any of the above compounds represented by Formulas I and II are incorporated in silver halide emulsions, these compounds are advantageously used in a gelatino-silver-chloride emulsion or a silver chloride emulsion containing small amounts of bromide or iodide. Silver halide emulsions in which the carrier is polyvinyl alcohol or hydrolyzed cellulose acetate can also be used. When the compounds are incorporated in the emulsion, they should be used in amounts from 2.5 to 25 grams per unit of silver halide formed from 1000 grams of silver nitrate. The same concentration of compounds should be present in the emulsion when the compounds are added by bathing the emulsion in a solution containing them. When the emulsion layer is bathed in a solution of the compound, the solution can contain up to about 5 percent by weight of the compound.

According to my invention, I provide the new compounds represented by Formula I above by heating to

2

gether a compound selected from those represented by the following general formula:

III

wherein Z has the values given above, with an alkali metal salt selected from those represented by the following general formula:

10 IV

wherein R has the values given above and M₁ represents a metal atom, such as an alkali metal atom, e. g. sodium, potassium, etc., and an amount of acid sufficient to liberate the free acid of the said alkali metal salt compound represented by Formula IV. Acids useful for this purpose comprise acetic acid, hydrochloric acid, sulfuric acid, etc., although it is to be understood that other acids can be used, since the purpose of the acid is simply to displace the metal atom of the compounds of Formula IV with a proton, i. e. a hydrogen atom.

The compounds represented by Formula III above can be prepared by condensing a compound selected from those represented by the following general formula:

25 V

wherein Z has the values given above, with maleic anhydride, such a process being described in my copending application Serial No. 285,302, filed on even date herewith. Typical aminobenzothiazole compounds included within the scope of Formula V above comprise, for example, the following: 2-aminobenzothiazole, 2-amino-5-bromobenzothiazole, 2-amino-6-bromobenzothiazole, 2-amino-4-chlorobenzothiazole, 2-amino-6-chlorobenzothiazole, 2-amino-7-chloro-4-methoxybenzothiazole, 2-amino-4-methoxybenzothiazole, 2-amino-5-methoxybenzothiazole, 2-amino-6-methoxybenzothiazole, 2-amino-6-ethoxybenzothiazole, 2-amino-4-n-butoxybenzothiazole, 2-amino-6-isobutoxybenzothiazole, 2-amino-4-methylbenzothiazole, 2-amino-6-methylbenzothiazole, etc.

The compounds selected from those represented by Formula II above can advantageously be prepared by mixing together a compound selected from those represented by Formula III above with ammonia to produce the ammonium salt of the compound of Formula III and thereafter mixing the resulting ammonium salt together with an alkali metal salt selected from those represented by Formula III and a sufficient amount of acid to liberate the free acid of the compound of Formula IV, i. e., a sufficient amount of acid to give the reaction mixture a pH below 7. Acids which have been found useful for the purpose of liberating the free acid of the compound of Formula IV comprise, for example, acetic acid, hydrochloric acid, sulfuric acid, etc., although other acids can be used to equal advantage.

The following examples will serve to illustrate more fully the manner whereby I prepare the new compounds of my invention.

Example 1.—2-(β -carboxy- α -thiocarbomethoxythiopropionamido)benzothiazole

75

2.5 g. of the 2-aminobenzothiazole salt of 2-(β -carboxyacrylamido)benzothiazole, 1.65 g. of methoxydithioformate, and 10 cc. of acetic acid were heated together on a steam bath for 15 minutes. There was a slight effervescence and the reactants dissolved. A white, crystalline precipitate then formed, and this was collected on a filter after chilling. The filter cake was then washed with ethanol and dried to give 1.0 g. of the desired product. It was recrystallized from ethanol as colorless needles, M. P. 207° C. with decomposition.

Example 2.—2-(β -carboxy- α -thiocarbethoxythiopropionamido)benzothiazole2.5 g. of 2-(β -carboxyacrylamido)benzothiazole, 2.7 g. of potassium ethoxydithioformate, and 10 cc. of acetic acid were heated together on the steam bath for 5 minutes with stirring. The thick, white precipitate was slurried in 10 cc. of ethanol and collected on a filter. The yield was 80 per cent. From acetic acid, the desired product formed opaque aggregates, M. P. 205° C.

Example 3.—2-(β -carboxy- α -thiocarbo-n-butoxythiopropionamido)benzothiazole4.0 g. of the 2-aminobenzothiazole salt of 2-(β -carboxyacrylamido)benzothiazole, 3.0 g. of potassium butoxydithioformate, and 10 cc. of acetic acid were heated on the steam bath for 10 minutes. The reactants first dissolved, and then crystallization occurred. There were then added 20 cc. of ethanol and the solid collected on a filter after chilling. The yield of desired product was 3.2 g. 80 per cent. From ethanol or aqueous acetic acid, the desired product formed fine needles, M. P. 196° C.

Example 4.—2-(β -carboxy- α -thiocarbo-n-octoxythiopropionamido)benzothiazole4.0 g. of the 2-aminobenzothiazole salt of 2-(β -carboxyacrylamido)benzothiazole, 2.5 g. of potassium n-octoxydithioformate, and 15 cc. of acetic acid were heated together on the steam bath for 10 minutes. The resulting white precipitate was collected on a filter and washed with ethanol. The yield of crude product was 2.5 g., 55 per cent, and had M. P. 190° C. On recrystallization from ethanol, it formed fatty flakes, M. P. 192° C.

Example 5.—2-(β -carboxy- β -thiocarbo-n-butoxythiopropionamido)benzothiazole2.5 g. of 2-(β -carboxyacrylamido)benzothiazole were dissolved in a solution of ammonia (2 cc.) having a specific gravity of 0.880 and water (20 cc.). Potassium n-butoxydithioformate (2.0 g.) was then dissolved in this solution at 20° C. With rapid stirring, 40 cc. of a 10 per cent solution of acetic acid was dripped in over a period of 2 minutes. A thick, pale yellow precipitate was formed and this was collected on a filter and washed with water. The yield was 2.3 g., 57.5 per cent, and had M. P. 232° C. (previous darkening). On recrystallization from ethanol, the desired product formed tiny, pale yellow needles, M. P. 233–235° C. (darkened at about 198° C.).

Example 6.—6-ethoxy-2-(β -carboxy- α -thiocarbo-n-butoxythiopropionamido)benzothiazole4.8 g. of 2-(β -carboxyacrylamido)-6-ethoxybenzothiazole (as its 2-amino-6-ethoxybenzothiazole salt), 2.0 g. of potassium n-butoxydithioformate, and 20 cc. of acetic acid were warmed on the steam bath for 5 minutes. The addition of 50 cc. of water to the clear solution precipitated a tacky solid which slowly hardened. From ethanol, it formed a pale violet powder, M. P. 178° C. The yield was 2.5 g.

acid were warmed on the steam bath for 5 minutes. The addition of 50 cc. of water to the clear solution precipitated a tacky solid which slowly hardened. From ethanol, it formed a pale violet powder, M. P. 178° C. The yield was 2.5 g.

In addition to serving as the liberating acid in the above examples, the acetic acid also acted as a solvent. Other diluents, such as ethanol, 1,4-dioxane, etc., can be used so long as sufficient acid is present to liberate the free alkoxydithioformic acid, which is necessary for the process of my invention. The product of Example II, for example, was obtained in similar yield when the amount of acetic acid was reduced to 1.0 cc. and 20 cc. of ethanol were used as the diluent.

I have also found that the new compounds of my invention can also be used in the vulcanization of rubber.

What I claim as my invention and desired secured by Letters Patent of the United States is:

1. A compound selected from the group consisting of those represented by the following two general formulas:

and

wherein R represents an alkyl group containing from 1 to 8 carbon atoms, M represents a member selected from the group consisting of a hydrogen atom and an alkali metal atom and Z represents the non-metallic atoms necessary to complete a heterocyclic nucleus of the benzothiazole series selected from the group consisting of benzothiazole and benzothiazole having substituted thereon a radical selected from the group consisting of bromine, chlorine, methyl, and an alkoxy group wherein the alkyl group is a primary alkyl group containing from 1-4 carbon atoms.

2. The compound having the following formula:

3. The compound having the following formula:

4. The compound having the following formula:

5. The compound having the following formula:

6. The compound having the following formula:

7. A process for preparing a compound selected from those represented by the following general formula:

wherein Z represents the non-metallic atoms necessary to complete a heterocyclic nucleus of the benzothiazole series selected from the group consisting of benzothiazole and benzothiazole having substituted thereon a radical selected from the group consisting of bromine, chlorine, methyl, and an alkoxy group wherein the alkyl group is a primary alkyl group containing from 1-4 carbon atoms, and R represents an alkyl group containing from 1 to 8 carbon atoms, comprising heating together a compound selected from those represented by the following general formula:

wherein Z represents the non-metallic atoms necessary to complete a heterocyclic nucleus of the benzothiazole series selected from the group consisting of benzothiazole and benzothiazole having substituted thereon a radical selected from the group consisting of bromine, chlorine, methyl, and an alkoxy group wherein the alkyl group is a primary alkyl group containing from 1-4 carbon atoms, an alkali metal salt selected from those represented by the following general formula:

wherein R represents an alkyl group containing from 1 to 8 carbon atoms and M₁ represents an alkali metal atom, and an amount of acid sufficient to liberate the free acid of the said alkali metal salt compound.

8. A process according to claim 7 wherein acetic acid is employed as the acid for liberating the free acid of the said alkali metal salt compound.

9. A process for preparing a compound selected from those represented by the following general formula:

5 wherein Z represents the non-metallic atoms necessary to complete a heterocyclic nucleus of the benzothiazole series selected from the group consisting of benzothiazole and benzothiazole having substituted thereon a radical selected from the group consisting of bromine, chlorine, methyl, and an alkoxy group wherein the alkyl group is a primary alkyl group containing from 1-4 carbon atoms and R represents an alkyl group containing from 1 to 8 carbon atoms, comprising mixing together a compound selected from those represented by the following general formula:

wherein Z represents the non-metallic atoms necessary to 20 complete a heterocyclic nucleus of the benzothiazole series selected from the group consisting of benzothiazole and benzothiazole having substituted thereon a radical selected from the group consisting of bromine, chlorine, methyl, and an alkoxy group wherein the alkyl group is a primary alkyl group containing from 1-4 carbon atoms, an alkali metal salt selected from those represented by the following general formula:

30 wherein R represents an alkyl group containing from 1 to 8 carbon atoms and M₁ represents an alkali metal atom, and a sufficient amount of acid to give the mixture a pH below 7.

35 10. A process according to claim 9 wherein acetic acid is used as the acid to give the mixture a pH below 7.
